UNITED STATES PATENT OFFICE

DORSEY F. ASBURY, OF BROOMES ISLAND, MARYLAND

RADIO APPARATUS

Application filed December 31, 1923, Serial No. 633,756. Renewed October 23, 1929.

My invention relates to radio apparatus, particularly receiving sets, employing plural tuning units, and my purpose is to provide means to effect adjustments of all tuning units of an apparatus simultaneously to correct relative relation for any particular wave length, to the end of rendering it possible to place an apparatus as an entirety in tune with an infinite number of wave lengths in an exceedingly short space of time, and to assure tuning of an apparatus with all wave lengths within its capacity upon simultaneous movement of all of its tuning units from one extreme adjustment thereto to the other.

So far as I am aware, in all radio receiving sets employing a plurality of tuning units, it is necessary to make a separate adjustment of each unit to tune the set with each different wave length, which means, of course, that if the receiving set employs, say, three tuning units, two-hundred and twenty-five adjustments are necessary to tune the set with seventy-five different wave lengths, this being true provided the correct adjustment of each tuning unit for a given wave length is previously known. On the other hand, if the correct adjustment of the tuning units for a given wave length is unknown, the number of adjustments necessary to secure tuning of the set with that or any particular wave length might be infinite. Again, assuming that only one wave length was being broadcasted out of a possible seventy-five, and further assuming that the correct adjustment of the tuning units was known for each wave length, it is manifest that seventy-four of the known adjustments might be made before the correct adjustment finally was made tuning the apparatus with the single wave length being broadcasted.

By the use of my invention all of the disadvantages inherent to the foregoing are eliminated, for by moving the tuning units simultaneously from one extreme adjustment to the other and constantly maintaining a correct tuning relation between them the apparatus is of necessity tuned with each wave length being broadcasted whether the correct adjustment of the tuning units for any or all wave lengths is or is not known.

My inventive idea, which finds expression solely in mechanical means, as distinguished from radiant energy or any theory with respect thereto, is capable of embodiment in different mechanical structures, certain of which are specifically shown in the accompanying drawings, but it is to be understood that the structures shown are merely intended as disclosures of the essential features and novel characteristics of my invention in preferred forms, and as best known to me at present, the scope of my concept being indicated by the terms of the appended claims.

In the drawings, wherein like characters of reference denote corresponding parts in the different views:

Figure 1 is a front elevation of a radio receiving set equipped with my invention;

Fig. 2, a top plan showing the essential parts of the receiving set shown in Figure 1 with my invention applied thereto;

Fig. 3, a transverse section on the line 3—3 of Figure 1;

Figure 4, a detail perspective showing a preferred arrangement of maintaining a reliable driving connection between an operator and a movable part of a tuning unit; and

Fig. 5, a diagrammatic view of a slightly modified arrangement for operating a plurality of tuning units by a common operator.

In the drawings I have shown my invention applied to a well known commercial type of radio receiving set consisting of a panel board 10 through which extend three parallel spaced shafts 11, 12 and 13 having fixed thereto, respectively, at their ends outwardly of the panel board dials 14, 15 and 16 for rotating said shafts to angularly adjust the movable parts of tuning units 17, 18 and 19, that are carried by them inwardly of the panel board.

The tuning units referred to will, of course, vary in different types of receiving sets, and in certain instances they may not all be of the same or like character, for in one instance they may consist of variable plate condensers in association either with or without other devices, such as coils, and in another instance they may consist of coils, known in

the art as variometers, in association either with or without other devices, as the particular construction of a given receiving set demands. Also all of the different tuning units 5 of a particular receiving set may be of like character, or only certain of them may be of like character, or they may all differ with respect to each other, the construction of a receiving set in these particulars being 10 immaterial to the operation of my invention so long as the movable parts of the respective tuning units have a predetermined adjustable relation with respect to each other.

In the particular receiving set herein illustrated the tuning units 17, 18 and 19 are of like character, each including essentially a variable plate condenser consisting of a stator *a* and a rotor *b* as shown in detail in the transverse section, Fig. 3, which is an illustration 20 of unit 18.

As aforementioned, the rotors *a* of the three tuning units shown are mounted for rotation with the shafts 11, 12 and 13 and dials 14, 15 and 16 respectively, and thus it is apparent that by rotating the respective dials the movable parts of the different tuning units 25 may be adjusted to tune the different units with different wave lengths.

My invention is based on the observation 30 that in certain types of receiving sets employing plural tuning units the ratio of movement of the movable parts of the different tuning units in changing the adjustment of the latter to tune the same with different wave lengths, 35 is fixed, by which I mean that to tune the receiving set herein illustrated for instance, a rotary movement of say 10° of dial 14 from a given starting point to tune the unit 17 with a particular wave length means that dial 15 must be rotated say 14° to correctly tune unit 40 18 with that wave length, and dial 16 must also be rotated say 10° to correctly tune unit 19 with that wave length. In other words, 45 once a correct adjustment of all tuning units is known for any particular wave length, the necessary adjusting movement of the tuning units with respect to each other to correctly tune all of them with any other wave length is predetermined and remains fixed.

In the receiving set herein illustrated, the amount of rotation required of dials 14 and 16 from a given starting point to correctly 50 tune the two tuning units associated therewith with a given wave length is the same, and this is true also of dial 15 and its tuning unit within certain predetermined limits of its adjustable movement, but within other predetermined limits the amount of adjustment required of dial 15 to tune its tuning unit with the same wave length varies with 55 respect to the adjustment required of the remaining units. In other words in the particular arrangement herein shown the angular velocity of dials 14 and 16 in moving their

associated tuning units from a position in tune with one wave length to a position in tune with another wave length is always the same, whereas within certain predetermined limits, the angular velocity of dial 15 in so moving its associated tuning unit varies. Stated another way, it is necessary at predetermined times to either speed-up or reduce the movement of the movable part of one or more or even all of the tuning units with 70 respect to one another in order to cause all of them to tune with the same wave length simultaneously.

In accordance with the foregoing I have provided means for adjusting all of the tuning units simultaneously so as to cause each unit to tune with a given wave length at the same instant, and also I have provided in combination with said means other means whereby an individual vernier adjustment of 75 the different tuning units may be made, so that if need be minor correction may be made in the adjustment of any one or more of the tuning units to secure an absolutely correct final adjustment after they have been initially simultaneously adjusted.

On shafts 11, 12 and 13, between the panel board 10 and the respective dials 14, 15 and 16 that are, as aforesaid, fixed to said shafts, I loosely mount three disks 20, 21 and 22, one 80 on each shaft, and in each disk I form a slot 23, while in each dial I rotatably mount a shaft 24, the inner end of which carries an eccentric 25 operating in its related slot 23 and the outer end of which is equipped with 85 an adjusting knob 26. Thus, by holding any given disk against rotation and turning the knob 26 to rotate the eccentric in association with that disk, rotation of the dial carrying that particular eccentric and consequent vernier adjustment of the tuning unit in association with that particular dial will be effected.

My means for adjusting all of the tuning units simultaneously consists of an operator 90 in the form of a light, flexible bar or rod 27 arranged in frictional driving contact with the peripheries of the disks 20, 21 and 22, so that by bodily shifting said operator longitudinally as, for instance, by means of a suitable knob or hand grip device 28 thereon, each of said disks will be rotated and, because of the aforementioned vernier connections between the respective disks and dials, the latter will be rotated and with them the shafts 11, 12 and 13, as well as the movable parts of the tuning units carried thereby. Disks 20, 22 in the receiving set herein shown are of the same diameter and consequently when the bar 27 is shifted, the same amount of rotation 95 is imparted to each of them. Disk 21, however, is chordally cut away as at 29 and bar 27 is provided with an offset 30 of such shape that it has rolling contact with the flap peripheral surface produced by said chordal 100 105 110 115 120 125 130

cut-away portion, and thus said disk 21 is caused to rotate, within the limits of its cut-away portion, at a different rate of speed from disks 20, 22. Also due to its chordal cut away portion, or in other words, the irregular peripheral outline of disk 21 and the offset 30 on operator 27, shifting of said operator causes rotation of said disk 21 at a predetermined variable angular velocity to cause the tuning unit associated therewith always to tune with a given wave length at substantially the same instant that the tuning units associated with disks 20, 22 tune therewith.

The chordal cut-away portion 29 of disk 21 and offset 30 on operator 27 provides, of course, for increasing the speed of rotation of said disk with respect to disks 20, 22 within the limits of said cut-away portion upon shifting of said operator. Obviously, however, it might be necessary to reduce the speed of disk 21 at predetermined times with respect to disks 20, 22, which could be accomplished by reversing the arrangement shown, or in other words, providing an enlargement on the disk and a recess in the operator. It follows also that in instances where it is necessary, the rotation of two or more disks may be reduced or increased with respect to each other or with respect to another disk in the same manner. Furthermore, any one or all of the disks may have plural reduced or enlarged portions as indicated by the full and dotted lines on disk 22, so that at one time the speed of rotation of a disk or disks may be increased and at another time reduced.

Operator 27 is utilized not only to simultaneously rotate the disks 20, 21 and 22, but also to hold said disks against rotation when vernier adjustments are being effected as aforementioned, and in order to hold said operator against the disks, so that it will drive them and also so that they will be held against rotation by one another during individual vernier adjustments of the tuning units, I have provided a plurality of pressure devices, one in association with each disk, and as shown each of said pressure devices consists of a pair of arms 31, 32, the former of which is pivoted at one end to the panel board 10, as at 33, and terminates at its free end adjacent to the free end of arm 32, which latter is connected at its other end to its associated shaft 11, 12 or 13 as the case may be. The free end of arm 32 is bent to overlie arm 31 and a pin 34 extends from arm 32 through arm 31 to maintain the free ends of said arms in proper relative relation, while surrounding said pin is an expansion coil spring 35 that reacts from arm 32 and as a consequence from the associated shaft 11, 12 or 13, against arm 31 to maintain a roller 36 that is carried by the latter arm, pressed against bar 27 and said bar pressed against the periphery of the associated disk 20, 21 or 22 in frictional driv-

ing contact therewith. By thus causing the pressures that hold the bar 27 in contact with the disks to react from the shafts on which the disks are mounted, all strains on said shafts which might otherwise have a tendency to change the correct relation of the blades of the rotary and stationary parts of the variable condensers are avoided. By such an arrangement it is manifest also that the respective pressure devices may be released selectively to permit each dial to be adjusted independently of the other dials.

A knob 37 may be provided on one or more of the rollers 36, so that said roller or rollers may be utilized as a vernier or verniers for shifting the operator 27, and the latter, if desired, roughened or may be faced with emery cloth or other suitable friction material 38 for contact with the peripheries of the disks and rollers to avoid slippage of said bar with respect to these parts.

In the modification shown in Fig. 5, the operator 27' is in the nature of a flexible rod and the disks 20', 21' and 22 are of different diameters and, if desired, of irregular shape so that upon shifting of said operator each disk will be rotated a correct amount, the rod 27' adapting itself to the different size disks and to irregularities in the peripheries thereof as is apparent.

I claim:

1. In radio apparatus, a rotatable shaft, a tuning unit a part of which is movable with said shaft, a member on said shaft, an operator engaging said member, a pivoted arm, a roller carried by said arm engaging said operator for driving the latter, and means reacting from said shaft against said arm to hold said roller in engagement with said operator.

2. In radio apparatus, a rotatable shaft, a tuning unit a part of which is movable with said shaft, a member on said shaft, an operator engaging said member, a roller engaging said operator, and yieldable means reacting from said shaft against said operator through said roller to hold said operator in engagement with said member.

3. In radio apparatus, a rotatable shaft, a tuning unit a part of which is movable with said shaft, a member on said shaft; an operator engaging said member, a pivoted arm, a roller carried by said arm and engaging said operator, a second arm connected at one end to said shaft and terminating at its other end adjacent to said first mentioned arm, and a spring between said first and last mentioned arms reacting from the latter against the former to hold said roller in engagement with said operator and the latter in engagement with the member on said shaft.

4. In radio apparatus, a plurality of tuning units a part of each of which is movable, a member common to a plurality of said movable parts for moving them collectively,

- means to impart fine adjustments to said member thereby to impart fine adjustments to said movable parts collectively, and a separate means carried by and movable with each movable part for imparting fine adjustments to said movable parts individually.
5. In radio apparatus, a tuning unit, a part of which is movable, a lineally reciprocal operator in rolling driving contact with said movable part, contacting portions of said operator and said movable part being of irregular form whereby said movable part is moved at varying velocities during movement of said operator at a constant velocity.
10. 6. In radio apparatus, a tuning unit including a member to be driven, a lineally reciprocal driving member in rolling driving contact with said member to be driven, a portion of one of said members which contacts with the other member being of irregular form whereby said driven member is moved at varying velocities during movement of said driving member at a constant velocity.
15. 7. In radio apparatus, a rotatable shaft, a tuning unit a part of which is movable with said shaft, a member on said shaft, an operator engaging said member, a roller engaging said operator, and yieldable means acting against said roller to hold said operator in engagement with said member.
20. 8. In radio apparatus, a plurality of tuning units a part of each of which is movable, an operator common to the movable parts of a plurality of said tuning units for driving them collectively, a member for driving said operator, and yieldable means acting through said member to hold said operator in driving engagement with said movable parts.
25. 9. In radio apparatus, a rotatable shaft, a tuning unit a part of which is movable with said shaft; a member on said shaft, an operator engaging said member, a pivoted arm, a member carried by said arm engaging said operator for driving the latter, and means reacting from said shaft against said arm to hold the member carried thereby in engagement with said operator.
30. 10. In radio apparatus, a rotatable shaft, a tuning unit a part of which is movable with said shaft, a member on said shaft, a reciprocal operator in driving engagement with said member, a pivoted arm, a roller carried by said arm engaging said operator, and means reacting from said shaft against said arm to hold said roller in engagement with said operator and the latter in engagement with said member.
35. 11. In radio apparatus, a tuning unit a part of which is movable, a lineally reciprocal operator in rolling driving engagement with an element of said tuning unit for moving the movable part thereof, and means for varying the velocity of said movable part during movement of said operator at a constant velocity.
40. 12. In radio apparatus, a pair of tuning units a part of each of which is rotatable, a lineally reciprocal operator common to said rotatable parts movable to rotate them collectively, said operator being in rolling contact with said rotatable parts, and means whereby said rotatable parts may be rotated at constant and also at variable velocities with respect to one another during movement of said operator at a constant velocity.
45. 13. In radio apparatus, a rotatable shaft, a tuning unit a part of which is movable with said shaft, a bearing for said shaft, a member on said shaft, an operator in driving engagement with said member, and yieldable means exclusive of said bearing reacting from said shaft to hold said operator in driving engagement with said member whereby said bearing is relieved of the force of said yieldable means.
50. 14. In radio apparatus, a tuning unit a part of which is movable, a pair of members one of which is loose and the other fixed with respect to said movable part, and an eccentric carried by the member that is fixed with respect to said movable part operating in a slot in the member that is loose with respect to said movable part.
55. 15. In radio apparatus, more than two tuning units, a part of each of which is movable, connections between the movable parts of the units to collectively secure adjustments of the units, and means included in said connections and carried by the movable part of at least one of the units, said means being operable to effect individual adjustment of the movable part of its related unit.
60. 16. In radio apparatus, more than two tuning units, a part of each of which is movable, connections between the movable parts of the units to collectively secure adjustments of the units, and means included in said connections and carried by the movable part of at least one of the units, said means being selectively operable to effect either individual adjustment of the movable part of its related unit or collective adjustments of the movable parts of all the units.
65. 17. In radio apparatus, more than two tuning units, a part of each of which is movable, connections between the movable parts of the units to collectively secure adjustments of the units, and means included in said connections and carried by the movable part of at least one of the units, said means being operable to effect individual adjustment of the movable part of its related unit, and also operable, when the movable part of its related unit is held against adjustment, to collectively adjust the movable parts of the remaining units.
70. 18. In radio apparatus, a tuning unit a portion of which is movable, a member adapted for movement relatively to the movable portion of the unit, and an eccentric device nor-

1,759,678

5

mainly effective to hold the movable portion of the unit and the member against relative movement and operable, when said member is held against movement, to move the movable portion of the unit.

In testimony whereof I hereunto affix my signature:
